UNITED STATES PATENT OFFICE.

JOHN F. O'CONNOR, OF CHICAGO, ILLINOIS, ASSIGNOR TO WILLIAM H. MINER, OF CHAZY,
NEW YORK.

HAND-BRAKE FOR RAILWAY-CARS.

1,300,465.

Specification of Letters Patent. Patented Apr. 15, 1919.

Application filed June 9, 1917. Serial No. 173,853.

To all whom it may concern:

Be it known that I, JOHN F. O'CONNOR, a citizen of the United States, residing at Chicago, in the county of Cook and State 5 of Illinois, have invented a certain new and useful Improvement in Hand-Brakes for Railway-Cars, of which the following is a full, clear, concise, and exact description, reference being had to the accompanying 10 drawings, forming a part of this specification.

This invention relates to improvements in hand brakes for railway cars.

One object of the invention is to provide 15 an efficient hand brake for railway cars and the like and which is of compact form, requiring a minimum amount of metal and relatively inexpensive to manufacture.

Another and more specific object of the 20 invention is to provide a hand brake of the type indicated wherein the necessity of coiling a chain around a drum, as the brake chain is tightened, is avoided.

In the drawing forming a part of this 25 specification, Figure 1 is an elevational view of a hand brake embodying my improvements. Fig. 2 is a vertical, sectional view, taken substantially on the line 2—2 of Fig. 1, the chain being omitted. Figs. 3 and 4 30 are vertical, sectional views, taken substantially on the lines 3—3 and 4—4 of Fig. 2. Fig. 5 is a horizontal, sectional view, taken substantially on the line 5—5 of Fig. 1. Fig. 6 is an enlarged detail sectional view, 35 taken substantially on the line 6—6 of Fig. 3, and illustrating more particularly the arrangement of pawl. And Fig. 7 is a view corresponding to Fig. 2, but illustrating a different embodiment of the invention.

40 In said drawing, and referring to the construction illustrated in Figs. 1 to 6, 10 denotes the wall of a car to which the improved hand brake is adapted to be applied. The brake, as shown, comprises an inner 45 plate 11 fitting directly against the wall of the car, an outer hood or casing member 12 riveted or otherwise secured to the car wall, as indicated at 13; 14 a sprocket wheel; 15 the chain leading to the brake proper; 16 50 the operating lever; and 17 the locking dog.

The casing 12 is of substantially cylindrical form having an outer wall 18 and circular side wall 19, the latter being recessed at the bottom, as most clearly indicated in Fig. 2 at 20, in order to permit the

necessary movements of the operating lever 16 and the entrance and exit of the chain 15. The hood 12 is provided with an annular shoulder at its inner end, as indicated at 21, which coöperates with the edge of the plate 60 11 and is thereby adapted to hold the latter securely in place against the wall.

The plate 11 is provided with a preferably integral hollow bearing 22 on which the sprocket wheel 14 is rotatably mounted. 65 The sprocket wheel 14 is shown as of substantially rectangular form (see Fig. 3) and is provided in its periphery with suitable notches or recesses 23 and 24 to receive the links of the chain 15 in the manner shown 70 most clearly in Fig. 3 and so that, as the sprocket wheel 14 is rotated, the chain 15 is passed over the sprocket wheel positively in a direction dependent upon the direction of rotation of the sprocket wheel. The 75 sprocket wheel 14 is also preferably provided with an integral ratchet wheel 25 on one side and a second ratchet wheel 26 on the other side. The ratchet wheel 25 forms a suitable bearing for an annular collar 27 80 formed on the upper end of the operating handle 16 whereby the latter is permitted an oscillation during the winding up of the chain. The operating lever 16, near its upper end and on the lower side of the ratchet 85 wheel 25, is provided with a pivoted pawl 28 adapted to coöperate with the ratchet wheel 25 and said pawl 28, as most clearly shown in Fig. 6, is provided with a weighted arm 29 to overbalance the pawl 28 and automatically throw the latter into engagement with the ratchet wheel 25 under the influence of gravity, except under the conditions 90 hereinafter described.

The normal position of the operating han- 95 dle 16, which hangs under the influence of gravity, is as shown in Figs. 1 and 3, and in this position of the operating handle, it is desirable that the pawl 28 be disengaged from the ratchet wheel 25. To accomplish 100 this, the casing 12 is provided on its inner side, in the position most clearly illustrated in Fig. 3, with a stop 30 against which the arm 29 engages when the operating lever 16 reaches its normal position and whereby the 105 pawl 28 is thrown into inoperative position, as will be understood.

In order to automatically hold the chain 110 in any of its adjusted positions, the locking dog 17 is provided, the same having a shoul-

der 31 which coöperates with the ratchet wheel 26, said dog 17 being pivoted, as indicated at 32, and so arranged that it also acts under the influence of gravity, to assume an operative position. It is provided with an extension or handle proper 33 by which it may be disengaged whenever desired.

As clearly shown in Fig. 1, the brake chain 15 is provided with a loop portion at its upper end which takes over the sprocket wheel 14. The condition of this loop and the remainder of the chain in normal or release condition of the brake, is as shown in Fig. 1. When the operator desires to apply the brakes, he oscillates the lever 16, thus causing a rotation of the sprocket wheel in a clockwise direction, as the same is viewed in Figs. 1 and 3. This consequently causes the pulling up of the left hand portion of the loop of the chain, as viewed in Fig. 1, and permits the right hand portion of said loop to fall or hang loosely. Also should there be any appreciable amount of slack in the sprocket chain, the operator can readily and rapidly take up said slack by pulling downwardly on the right hand portion of the loop of the chain before he begins to manipulate the lever 16. The chain is released by actuating the dog 17, as hereinbefore described.

With the arrangement heretofore described, it is apparent that there is no waste of material employed in the winding element for the chain, due to the fact that it is unnecessary to provide the necessary space for coiling the chain as has heretofore been customary. The brake is therefore unusually compact, light, and can be put in smaller spaces than brakes of a somewhat similar type heretofore used and at the same time without sacrificing any strength or ease of operation.

In the modification illustrated in Fig. 7, the arrangement of parts is substantially the same as that shown in the other figures except that the bearing 122 from the base plate 111 is made conical and with the upper surface 40 thereof extending horizontally or, stated in another manner, with the axis of the conical bearing 122 inclined slightly upwardly. A corresponding change in the shape of the inner bearing surface 41 of the

sprocket wheel 114 is made, thus inclining the sprocket wheel so that it is perpendicular to the axis of the conical bearing. With this arrangement, it is obvious that the operating lever 116 is inclined away from the chain, which is represented conventionally by the dot and dash line 42, thus giving a somewhat greater clearance at the lower end 60 of the operating lever for the hand of the operator. Furthermore, the conical bearing 122 affords a somewhat stronger construction due to its tapered formation which places the lower portion of the bearing under compression when tension is placed on the sprocket wheel 114. The operation is the same as that for the other construction.

I claim:

1. In a brake for railway cars and the like, 70 the combination with a sprocket wheel rotatably mounted about a substantially horizontally extending axis, of a brake chain co-operable with said sprocket wheel, means for rotating said sprocket wheel step by step, 75 said means including an operating handle oscillatably mounted about said axis, devices interposed between said handle and the wheel, said handle normally depending under the influence of gravity and said devices 80 being in inoperative position.

2. In a brake of the character described, the combination with a housing adapted to be secured to a car wall, of a chain sprocket wheel rotatably mounted within said housing, a pawl and ratchet mechanism including a gravity actuated pawl for rotating said wheel step by step, and means for locking said wheel in position.

3. In a brake of the character described, 90 the combination with a housing adapted to be secured to a car wall, of a sprocket wheel rotatably mounted within said housing and having two ratchet wheels associated therewith, an operating lever having a gravity 95 controlled pawl coöperable with one of said ratchet wheels, a gravity controlled locking dog coöperating with the other of said ratchet wheels, and a brake chain extending over said sprocket wheel.

In witness that I claim the foregoing I have hereunto subscribed my name this 31st day of May, 1917.

JOHN F. O'CONNOR.
